[57] CLAIM

The ornamental design for connector, substantially as
shown and described.

DESCRIPTION

FIG. 1 is a bottom perspective view of the connector
showing my new design;

FIG. 2 is a side view of the connector;

FIG. 3 is a bottom view of the connector;

FIG. 4 is a top view of the connector;

FIG. 5 is a view of the side of the connector opposite
that shown in FIG. 2;

FIG. 6 is a view of my connector taken at the plug end
thereof; and

FIG. 7 is a view of the end of my connector opposite
that shown in FIG. 6.
